UNITED STATES PATENT OFFICE.

ARTHUR KELLY EVANS, OF TORONTO, CANADA.

DESIGN FOR A ROPE-GRIP.

SPECIFICATION forming part of Design No. 23,448, dated July 10, 1894.

Application filed May 17, 1894. Serial No. 511,612. Term of patent 14 years.

To all whom it may concern:

Be it known that I, ARTHUR KELLY EVANS, a subject of the Queen of Great Britain, residing at the city of Toronto, in the county of 5 York, in the Province of Ontario, Canada, have invented and produced a new and original Design for Rope-Grips, of which the following is a specification.

Figure 1, is a front perspective view of my design. Fig. 2, is a view from the opposite side.

In the drawings like letters of reference indicate corresponding parts in each figure.

The design consists of a flat body portion 15 A formed with two circular openings B and

terminating at one end in a hook C curving out from the body in a plane at about right angles thereto and at the opposite or lower end in a hook D parallel to the body portion, the hook C being directly above and in rear of the body plate while the hook D is one side thereof.

What I claim is—

The design for a rope grip as shown and described.

ARTHUR KELLY EVANS.
